UNITED STATES PATENT OFFICE

CHARLES G. FROEHLICH, OF BIRMINGHAM, ALABAMA

WALL ANCHOR

Application filed March 23, 1928. Serial No. 264,181.

My invention relates to means for securing and supporting an outer masonry building wall, such as of brick or stone, to the frame work or inner structure of a building, and has for its object the provision of a device of the character designated which shall be simple of design, easy of manufacture and which shall be adjustable as to position.

10 A further object of my invention is to provide a wall anchor for brick or stone walls which shall be readily adjustable to position in a selected course of brick or stone in the wall and which shall furnish both vertical 15 and lateral support to the wall.

A still further object of my invention is to provide a wall anchor especially adapted to support and retain a brick or stone wall against a reinforced concrete structure and 20 which shall embody a wall supporting and tying element adjustable to position between the courses in the masonry together with novel wedge means to hold it in position, whereby, once located in position in the wall, vertical 25 strain thereon serves to tighten the wedging means.

As is well known in the building art, especially in constructing large structures, it is necessary to interpose anchors at regular 30 intervals in the wall to serve both as a vertical and a lateral support to the outer masonry. This has usually been accomplished by arranging bolts with outwardly extending threaded ends in the forms before the reinforced concrete girders of the building are 35 poured, so that the bolts are embedded in the concrete, and afterward securing angle bars to the bolts with flanges extending outwardly into the masonry wall. While this forms a 40 sturdy means of support when properly located, it offers considerable difficulties and expense in the way of application. For example, the angle bars must have holes provided therein to receive the bolts thereby requiring accurate spacing of the bolts, and in pouring the concrete girders the bolts often 45 become displaced so that they do not come directly opposite the holes, whereupon the angles must again be drilled to match the 50 bolts. Furthermore, the courses in the outer

wall rarely come directly opposite the location of an angle bar so that a flange of the angle bar can lie between the courses without thickening the mortar joint or otherwise spoiling the symmetrical outer appearance of the building.

These and other difficulties are overcome by means of my invention and I have provided a wall anchor which is capable of being shifted both laterally and vertically to its position in the masonry wall and which requires no drilling of holes or cutting of the angle supports. Briefly, my invention comprises an anchor proper which is partially 55 embedded in the concrete girders of the building or is otherwise suitably secured thereto, and which embodies angle supporting means 60 adjustable vertically with respect to the anchor. The angle bar is supported on the vertically 65 adjustable means by an extremely simple base member and an upper member integral with the base member and turnable over the vertical flange of the angle bar. The wedge means employed to hold the angle 70 supporting means in place is of such a character that downward strain on the angle bar serves 75 to tighten the wedges and hold the angle bar more firmly in place.

Apparatus embodying features of my invention is illustrated in the accompanying drawings, forming a part of this application, in which

Fig. 1 is a front elevational view of the angle holding parts of my improved wall 85 anchor;

Fig. 2 is a cross sectional view taken along the line II—II of Fig. 1 and showing the masonry supporting angle bar in place and showing in dotted lines the upper outwardly 90 extending portion of the angle support turned downwardly to hold the angle bar in place;

Fig. 3 is a sectional view along the line III—III of Fig. 1 and showing the angle bar holding parts embedded in a concrete 95 girder.

Fig. 4 is a view in side elevation showing the method of embedding the anchor in a concrete girder;

Fig. 5 is a vertical cross sectional view 100

of the wall anchor attached to a concrete girder and supporting and anchoring a masonry wall; and

Fig. 6 is a view similar to Fig. 5 showing a modified form of my invention as applied to a wood frame structure and used to retain a veneer wall of masonry.

Referring now to the drawing, particularly to Figs. 1 to 5, for a better understanding of my invention, my improved wall anchor comprises a retaining member 10 which may be made of relatively light sheet steel, or other suitable metal, and provided with rearwardly extending anchoring means 11 and 12, formed by bending the upper and lower portions of the retaining member 10 rearwardly. The members 11 and 12 are provided with holes 13 and 14 so as to be better held in a concrete girder. In addition to the rearwardly bent portions 11 and 12 there are also provided rearwardly extending tongues 16 and 17 which are dovetail in shape, as seen in Fig. 2, and which are formed by cutting out the retaining member 10 and bending back the portions cut out, as seen in Fig. 3.

The retaining member 10 is made with downwardly converging sides which are bent over to form slots 18 and 19. An angle bar supporting member 21 has one side 22 inclined to the longitudinal axis of the member 10 and fitting in the slot 18. The other side 23 of the angle bar supporting member 21 lies parallel with the longitudinal axis of the retaining member 10 when the parts are assembled as seen in Fig. 1. A wedge member 24 lies within the slot 19 and bears against the side 23 of the angle bar supporting member 21. The angle bar supporting member is provided with a lower arm 26 and an upper arm 27 which serves to support an angle bar 28 forming an anchoring shelf for a masonry wall 29, as seen in Fig. 5. In supporting the angle bar 28, the lower edge thereof is placed on the lower arm 26 of the supporting member 21 and the upper arm 27 is bent downwardly over the upper side of the angle bar 28.

It will be seen, with this construction, that as the weight of the wall 29 bears downwardly on the angle bar 28 the load transmitted to the member 21 forces said member more tightly into engagement with the sides of the slot 18 and more tightly against the wedge 24 resting in the slot 19. While the device so far described provides all lateral support for the wall which is normally needed, I provide slotted holes 31 and 32 in the member 21 and provide bosses 33 and 34 on the retaining member 10 and having interiorly threaded holes 36 and 37 arranged to come opposite one of the holes 31 or 32. A screw 38 may be employed to hold the supporting member 21 in place, once its location has been established.

In use, the retaining members 10 are secured in a concrete girder 41 at suitable intervals, in a manner to be described later, as

the main portion of the building is being erected. As the outside masonry wall 29 is built up to the retaining members 10, the angle bar supporting members 26 are adjusted by means of the wedge 24, to the proper height for the angle bars to lie in the joints between the courses in the masonry. The wedge 24 is then driven in to tighten the supporting member 21 and the screw 38 is then tightened down and the angle bar 28 is put in place with the upper arm 27 of the supporting member 21 bent downwardly over the side of the angle bar 28.

It will be seen that inasmuch as there are no holes to be drilled in the angle bars, or no bolts in the concrete girder, the angle bars may be shifted from side to side to match the openings in the building and may be adjusted vertically to come opposite the joints in the courses of the masonry. Furthermore, the angle bar 28 is permitted a limited adjustment outwardly from the building by varying the location of the bend in the upper arm 27 and by the mason sticking mortar or other suitable backing behind the angle bar.

The retaining members 10 are put in place in the concrete girders by tacking them to the sides of forms such as 46, shown in Fig. 4, before the girders are poured. At this time, in order to prevent the slots 18 and 19 filling with the concrete and to leave space for the supporting member 21 to be inserted after the girder is poured and the form removed, a wooden insert 47 of suitable length and fitting in the slots 18 and 19 is inserted in the slots. By referring to Fig. 3 it will be seen that this method of embedding the retaining members 10 in the concrete girder provides a side support of concrete for the walls of the slots 18 and 19 which provision permits the use of much lighter material in the retaining member 10 than would otherwise be possible.

Referring now to Fig. 6, I show a modified form of my invention wherein the main structure of the building with which it is employed embodies wooden girders or frame work 51. With this form of my invention, I provide a retaining member 52 adapted to lie flat against the wooden girder 51 and having a suitable number of holes 53 to receive anchoring members such as spikes 54 driven into the girder 51. The other parts of the device are the same as has been described previously and the description need not be repeated.

From the foregoing it will be apparent that I have devised an improved wall anchor, simple of construction, readily adjustable in position to accommodate an outer masonry wall of the building and one which forms a sturdy support for such a wall.

While I have shown my invention in but two forms, it will be obvious to those skilled in the art that it is not so limited, but is

susceptible of various other changes and modifications, without departing from the spirit thereof, and I desire, therefore, that only such limitations shall be placed thereupon as are imposed by the prior art or as are specifically set forth in the appended claims.

What I claim is:

1. A wall anchor for an outer masonry wall of a building comprising a member secured to the building structure and provided with downwardly converging lateral slots, an angle bar supporting member having one side resting in one of the slots, a wedge member cooperating with the other side of the angle bar supporting member and the other slot to hold the angle bar supporting member in place and permitting vertical adjustment of the position thereof, and an angle bar supported by the angle bar supporting member and having a flange projecting into the masonry wall.

2. A wall anchor as set forth by claim 1 wherein the angle bar supporting member embodies upper and lower outwardly extending portions for receiving between them one side of the angle bar, the lower edge of the angle bar resting on the lower outwardly extending portion and the upper outwardly extending portion being turned downwardly over the upper side of the angle bar.

3. A wall anchor for the outer masonry wall of a building comprising a retaining member secured to the building structure and provided with downwardly converging slots, an angle bar supporting member having one side resting in one of the slots, and a wedge member coacting with the other side of the angle bar supporting member and disposed in the other slot.

4. A wall anchor for the outer masonry wall of a building comprising a retaining member secured to the building structure and provided with downwardly converging slots, an angle bar supporting member having one side resting in one of the slots, a wedge member coacting with the other side of the angle bar supporting member and disposed in the other slot, upper and lower outwardly extending arms provided on the angle bar supporting member, and an angle bar resting on the lower arm and having the upper arm turned downwardly over one of its flanges.

5. A wall anchor for the outer masonry wall of a building comprising a retaining member secured to the building structure and provided with downwardly converging slots, an angle bar supporting member having one side resting in one of the slots, a wedge member coacting with the other side of the angle bar supporting member and disposed in the other slot, upper and lower outwardly extending arms provided on the angle bar supporting member, an angle bar resting on the lower arm and having the upper arm turned

downwardly over one of its flanges, and screw and slot means for securing the angle bar supporting member to the retaining means.

6. A wall anchor for the outer masonry wall of a building having concrete girders comprising a retaining member having rearwardly extending anchoring means extending into the concrete and having a body portion provided with downwardly converging slots, an angle bar supporting member having outwardly projecting arms and having one side resting in one of the slots, a wedge member coacting with the other side of the angle bar supporting member and disposed in the other slot, and an angle bar resting on the lower outwardly projecting arm and held in place by the upper arm.

In testimony whereof I affix my signature.

CHARLES G. FROEHLICH.
